United States Patent Office.

LAURITZ ANDERSON, OF CHICAGO, ILLINOIS.

Letters Patent No. 97,855, dated December 14, 1869.

IMPROVEMENT IN GATES FOR SWINGING BRIDGES.

The Schedule referred to in these Letters Patent and making part of the same.

To all whom it may concern:

Be it known that I, LAURITZ ANDERSON, of Chicago, in the county of Cook, and State of Illinois, have invented a new and valuable Improvement in Gates for Swinging Bridges; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of my invention, in perspective, as the draw is moving from the bridge-head.

Figure 2 is a representation of the gate attached to bridge-head, as it appears when the draw is closed and gate down.

Figure 3 is a sectional view.

My invention relates to draw bridges, and consists, mainly, in the construction and novel arrangement of devices whereby the sheer ends of the bridge-heads are automatically closed by gates, which rise in place as the draw moves away.

The letter A, of the drawings, designates the draw, only one end of which is shown, as the gate at the other end is constructed and operated in like manner.

The letter a' designates a slot or track formed in the end of the draw, and lined with suitable metal.

The bridge-head B is provided with a cross-beam, C, to the upper surface of which are secured three plates of metal, through which pass the three perpendicular guide-rods of the gate.

The gate D consists of three perpendicular rods, d, d', and d'', to the upper ends of which is secured the horizontal bar h.

Between the rods are fastened the braces k k', and just above the point at which these braces abut against the central rod h, a pin, n, is formed, about which rotates an anti-friction roller, which plays in the slot a' in the end of the draw.

To the lower end of the central guide-rod d is attached one end of a chain, which, passing over the pulley p, is attached by the other end to a weight, I, which counterbalances the weight of the gate.

The letter S designates a lever, the lower end of which is formed into a shelf or ledge, which, by the action of the spring c, is drawn under the end of the

rod d, when the draw, moving away, leaves the upper arm of the lever free.

This upper arm is an elbow projected above the surface of the cross-beam C, so that the draw-frame, in passing over it, will press it down, and thereby move the ledge from under the rod d, allowing the gate to descend.

The operation of the gate is as follows:

The draw being closed, the gate is down, and its anti-friction roller n is in the lowermost part of the slot of the draw. At the same time, the elbow of the lever S is depressed, and the ledge at the end of its lower arm is away from the rod d. Now, as the draw moves away in swinging upon its pivot, the slot a' in its end gradually carries up the roller n, and with it the gate D. At last the slot a' leaves the roller altogether, but the gate is prevented from falling by the balance-weight I, and by the ledge on the lower end of the lever S, which, as soon as the end of the draw is removed, is drawn, by the action of the spring c under the lower end of the rod d.

In closing the draw, the open end of the slot a' catches the roller n, and as the frame of the draw, at the same time, by pressing on the elbow-arm of the lever S, frees the lower end of the rod d, the gate is pulled gradually down, between the bridge-head and end of the draw, until the horizontal bar h is below the planking.

The weight I being just sufficient to counterbalance the weight of the gate D, offers little or no resistance to the movement of the draw, therefore requiring for its operation the expenditure of no more power than is at present necessary.

What I claim as my invention, and desire to secure by Letters Patent, is—

The gate B, counterpoised by a weight, and provided with a projecting pin or stud, n, in combination with the groove a' in the end of the turning bridge, and the locking-lever S, all constructed and arranged to operate substantially as described.

In testimony that I claim the above, I have hereunto subscribed my name, in the presence of two witnesses.
